The ornamental design for a light box for a transparency adapter, as shown and described.

DESCRIPTION

(21) Appl. No.: **29/152,636**

FIG. 1 is a top plan view of a light box for a transparency adapter;

(22) Filed: **Dec. 20, 2001**

FIG. 2 is a bottom plan view thereof;

(51) LOC (7) Cl. **26-02**

FIG. 3 is a left side elevation view thereof of which the right side elevation view is a mirror image;

(52) U.S. Cl. **D26/37**; D10/104; D14/433;

D16/225

(58) **Field of Search** D14/432, 420-425,

D14/433; D10/104, 106; D26/37; 40/361-367,

574, 575; D16/221, 225, 235

FIG. 4 is a front elevation view thereof;

FIG. 5 is a rear elevation view thereof;

FIG. 6 is a top front perspective view thereof; and,

FIG. 7 is a top front right perspective view thereof.

Features shown in dashed lines in the drawing figures form no part of the claimed design.
